UNITED STATES PATENT OFFICE.

MAX BLOOMSTEIN, OF NASHVILLE, TENNESSEE.

SHOE-SHINING DEVICE.

1,375,625.

Specification of Letters Patent. Patented Apr. 19, 1921.

Application filed September 23, 1920. Serial No. 412,179.

To all whom it may concern:

Be it known that I, MAX BLOOMSTEIN, a citizen of the United States, and a resident of Nashville, in the county of Davidson and 5 State of Tennessee, have invented certain new and useful Improvements in Shoe-Shining Devices; and I do hereby declare the following to be a full, clear, and exact description of the invention, such as will 10 enable others skilled in the art to which it appertains to make and use the same.

This invention relates to improvements in shoe shining devices,—one object of the invention being to provide a simple, compact and substantial device of the character 15 specified which can be cheaply manufactured; which can be packed in a small space for use of travelers, and which shall be convenient to operate.

20 With this and other objects in view, the invention consists in certain novel features of construction and combination of parts as hereinafter set forth and pointed out in the claims.

25 In the accompanying drawings, Figure 1 is a view of a shoe shining device embodying my invention. Fig. 2 is an end view, and Fig. 3 is a longitudinal sectional view.

1 represents a rectangular frame constructed of stout wire and comprising side 30 members 2, 2, and end members 3, 3.

A block 4, preferably of wood, extends from one end member to the other and at its ends is provided with grooves 5 to receive 35 said end members so that said block shall be so disposed that its upper face will lie approximately flush with the upper faces of said end members and said block is of such thickness that it will depend an 40 appreciable distance below the horizontal plane of the under faces of the wire frame 1, thus causing said wire frame to be disposed a sufficient distance above the support on which the device may be placed to

45 permit the free movements of a polishing cloth 6 which is caused to pass about the side members of the wire frame and over the shoes of the user.

A sheet metal facing plate 7 (preferably 50 of galvanized iron) is located upon the wooden block 4 and may be secured thereto

by means of indentations 8 or by other suitable fastening means. At respective ends the metal facing sheet is bent downwardly over the end members of the wire frame so 55 as to form flanges 9 which are secured to the ends of the wooden block by means of indentations 10 or other suitable fastening means, and in this manner the wooden block as well as the metal spacing sheet are 60 securely fastened to the ends of the wire frame.

It will be noted that the wooden block and its covering sheet are considerably less 65 in width than that of the wire frame and thus openings 11 of adequate size are afforded for the free passage of the polishing cloth.

Having fully described my invention 70 what I claim as new and desire to secure by Letters Patent, is:

1. A shoe shining device comprising a rectangular wire frame, a block extending from end to end of said frame and having grooves in the upper surfaces at its ends to receive the end members of said frame, the said block being narrower than the wire frame so as to leave looped openings continuously throughout the length of the block, and a plate secured to said block and 75 covering the ends of the wire frame within the grooves in the block, the said plate being secured to the ends of the block and operating to hold the wire frame in place.

2. A shoe shining device, comprising a rectangular wire frame, a wooden block narrower than the rectangular wire frame, the said block being notched at its ends and extending from end to end of said wire frame and depending below the plane 80 thereof, and a sheet metal facing plate secured upon said wooden block and having flanges embracing the end members of the wire frame and secured to the ends of said wooden block.

In testimony whereof, I have signed this specification in the presence of two subscribing witnesses.

MAX BLOOMSTEIN.
